(57) **CLAIM**

The ornamental design for an elevated batten, as shown and described.

DESCRIPTION

FIG. 1 is a perspective view of an elevated batten showing the design;

FIG. 2 is a top plan view of the elevated batten of FIG. 1; FIG. 3 is a bottom plan view of the elevated batten of FIG. 1;

FIG. 4 is a front elevational view of the elevated batten of FIG. 1;

FIG. 5 is a rear elevational view of the elevated batten of FIG. 1;

FIG. 6 is a left elevational view of the elevated batten of FIG. 1;

FIG. 7 is a right elevational view of the elevated batten of FIG. 1;

FIG. 8 is a detailed right perspective view of the elevated batten of FIG. 1;

FIG. 9 is a detailed bottom plan view of the elevated batten of FIG. 1;

FIG. 10 is a detailed front elevational view of the elevated batten of FIG. 1; and,

FIG. 11 is a detailed right elevational view of the elevated batten of FIG. 1.

The long dash-dot broken lines in the drawings define the boundaries of the claim and form no part thereof. Dash-dash broken lines depict portions of the elevated batten that form no part of the claimed design. The broken away symbols in the drawings are used to indicate that any portion of the elevated batten between the break lines forms no part of the claimed design.
